UNITED STATES PATENT OFFICE.

JOHN T. MEATS, OF TAUNTON, MASSACHUSETTS.

QUILLING-MACHINE.

SPECIFICATION forming part of Letters Patent No. 444,499, dated January 13, 1891.

Application filed July 8, 1887. Serial No. 243,723. (No model.)

To all whom it may concern:

Be it known that I, JOHN T. MEATS, of Taunton, in the county of Bristol and State of Massachusetts, have invented an Improvement 5 in Quilling-Machines, of which the following description, in connection with the accompanying drawings, is a specification, like letters on the drawings representing like parts.

This invention has for its object the improvement of winding or quilling machines, whereby greater simplicity, durability, and strength are attained.

My invention consists, essentially, in the frame of a bar having packed bearings for a spindle and provided with a horizontal extended arm having at its upper side a concaved shelf to receive a full bobbin and having a depending horizontally-slotted web integral therewith, combined with a detachable 20 guide or trumpet and with a horizontally-adjustable inclined bar attached to the said web, substantially as will be described; also, in the winding or traverse mechanism for distributing the yarn on the bobbin, of transverse shafts having adjustable guides, spring-connected arms, and forked links attached thereto, having toe-pieces at their inner ends, combined with a cam against the periphery of which bear the toe-pieces, whereby the 25 traverse mechanism moves at a faster speed when the yarn is being wound upon the bobbin from its point toward its base than when in the opposite direction to lay a long spiral or binding thread, substantially as will be described.

Figure 1 is a vertical cross-section of a sufficient portion of a winding-machine to enable my invention to be understood. Fig. 2 is a partial front elevation of the machine shown 40 in Fig. 1, it representing one thread-guide, trumpet, and spindle in position on one arm *c*, and next to it an arm with the trumpet and thread-guide removed, and next beyond an arm *c* in section, the central part of the machine being broken out to save space in the drawing; and Figs. 3 and 4, details to be referred to.

The frame-work *A*, of suitable shape to hold the various parts, has a main drum-shaft *A'*, 45 provided with usual fast and loose pulleys, said shaft having a spindle-driving drum, as *A*², and a toothed gear *A*³, which engages a

toothed gear *B*, of like diameter, secured to the shaft *B'*, provided with a second spindle-driving drum *B*², the said drums in practice 55 actuating bands which are extended about them and over the whirls *a' b'*, rigidly secured on the spindles *a b*, all in usual manner, the said bands being herein omitted to avoid unnecessary lines in the drawings. 60

The spindles *a* on one side of the machine are placed opposite the spaces between the spindles *b*, located on the other side of the machine, the rear ends of the spindles *a* terminating beyond both of the bearings *d d*, as 65 shown by the line 80 at the left of Fig. 1, the dotted line 81 at the right-hand side of the said figure showing the rear end of the spindle *b*. The said spindles have fast upon them, respectively, whirls *a' b'*, embraced by 70 loose yokes *a² b²*, the said yokes having pivoted on them similar arms *a³ b³*, on which are hung weighted links *a⁴ b⁴*, the said arms having pins 2 to rest upon bifurcated inclined arms *a⁵ b⁵*, adjustably attached by bolts, as 75 3, to a slotted web at the lower portion of the arms *c*, formed as integral parts of the spindle-bars *C*, extended lengthwise of the frame, the said bars *C* being notched at their upper side at 23, as shown in Fig. 2, for the reception 80 of the spindles *a b*, the notched portions of the said bars constituting bearings for the spindles. These bars *C* are grooved longitudinally at their upper sides, as at 22, (see Fig. 3,) to form a channel for the reception of 85 a suitable packing, as 4, (see Fig. 1,) which, when saturated with oil, constitutes a suitable lubricant for the spindles. This packing and the grooves will be covered by a suitable cap, as *d*. 90

The adjustment of the inclined bars *a⁵ b⁵* by the bolts 3 enables the apparatus to be adapted to bobbins of different length. The nearer the bolt 3 to the outer end of the slot 6 the shorter the bobbin which can be wound, 95 for by that much the sooner will the pin 2 fall down the inclined heel 12 of the bar upon the support 13, which in practice will preferably be made hook-shaped, as shown, a short lug 13^a, projecting beyond the end of the hook, 100 serving to prevent the bars *a⁵ b⁵* falling too low.

In practice each spindle will have a head or button 10, provided with a pin or pins 30,

extending from it outwardly, (see right of Fig. 1,) to enter usual notches in the base or head 15 of the bobbin, the pins rotating the bobbin in usual manner until the pin 2 of the 5 arm a^3 or b^3 arrives upon the inclined heel 12, when the yoke a^2 or b^2 will be given a quick backward stroke sufficient to withdraw the pins 30 of the button 10 from the bobbin, leaving the latter at rest with its end in the 10 guide or trumpet, from which latter it may be readily removed by slightly elevating the base of the bobbin, the usual tapering slot d^{15} , enlarging toward the large end of the 15 guide, aiding in permitting the bobbin to be tipped sufficiently to move the head or base thereof past the washers or buttons 10 and the studs or pins 30 at the ends of the spindles.

The arms c , integral with the spindle-bars 20 C , form very stiff and rigid supports for the shanks 16 of the conical guides or trumpets d^2 , each of the said shanks being adjustably connected by a bolt, as 9, to a slotted depending flange or lip 8 of an arm c , the said guides 25 being made adjustable, in order that they may be placed in concentric position with relation to the spindles. The action of the accumulating yarn on the bobbin guide or trumpet causes the spindle to be pushed inwardly, dragging the arm a^3 or b^3 up the incline of the arm a^5 or b^5 , the hardness of the winding depending upon the inclination of the said arm, the weighted rod a^4 or b^4 , jointed to the said arm a^3 or b^3 , at such time traveling 30 through the longitudinal slot made in the inclined arm a^5 or b^5 . The bobbin on the spindle b is shown as having received upon it but a small amount of yarn; but the bobbin on the spindle a is shown as more nearly filled. Extending the arms c outwardly from the bar C 35 enables me to keep the central part of the machine free for the operation of the whirls and yokes a^2 b^2 . The upper sides of the arms c are concaved to serve as supports for the wound bobbins while other bobbins are being applied to the spindles, or for empty bobbins.

Referring to the traverse mechanism or winding motion which distributes the yarn upon the bobbin, the guide - eyes f thereof, 40 one for each spindle, are composed of wire and are severally screwed into a block f' , which is clamped upon the rocking traverse-shaft f^2 , set-nuts f^* being employed to fix the wires in position after they have been screwed 45 for the proper distance into the block. Each shaft f^2 has a downwardly-extended arm f^3 , slotted as at 14, the said slots receiving within them pins or bolts 25 of the sliding forked links g g' , the said bolts being adjusted in 50 the said slots 14 according to the length of the taper of the bobbin to be wound with yarn, and being held in adjusted position by the washers t t' . (See Fig. 2.) Each bolt 55 has a shoulder against which the washer t' abuts, the said shoulder fitting loosely into a 60 suitable bearing in the links g g' .

The lower ends of the arms f^3 at opposite sides of the machine are connected together by a strong spiral spring f^6 , the latter acting normally to keep the guide-eyes in their outermost positions and to keep the toe-pieces g^2 70 adjustably attached to the said links by screws g^3 , pressed against the periphery of the cam m . These toe-pieces are slotted and by means of the screws g^3 are longitudinally 75 adjustable on the said links to determine the starting and stopping points for the guide-eyes f . The cam m referred to, located near one end of the frame, is mounted upon a stud m' , and the hub of the cam at each side is 80 grooved, as at m^2 , for the reception and guidance of the forked inner ends of the links g g' , and, as shown in Fig. 1, the toe-pieces g^2 are secured to the links g g' at opposite sides, thus enabling both toe-pieces to be acted upon 85 by one and the same narrow cam m . The hub of the cam m has attached to it a gear m^4 , engaged and driven by a small pinion m^5 , fast on a short shaft m^6 , having a toothed gear m^7 , engaged and driven by a pinion m^8 , 90 (shown best in Fig. 1, where the frame-work A and beam B^2 are broken out,) the said pinion being fast upon the shaft B' , carrying the drum B^2 . The cam m , driven as described, is shaped as fully shown in the drawings, (see 95 Fig. 1,) its periphery having a long gradually-inclined portion and a short re-entrant portion following, so that the motion imparted by it to the toe-pieces and links and thence to the thread-guides f is much quicker in one 100 than in the other direction, as thereby the coils of yarn are wound more closely together upon the bobbin when the winding is being done from the base of the bobbin toward its small end than in the other direction, the 105 yarn wound upon the bobbin while the thread-guides are moving the fastest serving as binding-threads.

I claim—

1. The traverse-shafts f^2 f^2 , having adjustable guides f , spring-connected arms f^3 , and forked links g g' attached thereto, having toe-pieces g^2 at their inner ends, combined with a cam m , against the periphery of which bear the toe-pieces, substantially as described. 110

2. The bar C , having packed bearings for a spindle and provided with a horizontal extended arm c , having at its upper side a concaved shelf to receive a full bobbin and having a depending horizontally-slotted web integral therewith, combined with a detachable guide or trumpet and with a horizontally-adjustable inclined bar a^5 or b^5 , attached to the said web, as and for the purposes set forth. 120

In testimony whereof I have signed my 125 name to this specification in the presence of two subscribing witnesses.

JOHN T. MEATS.
